BELT DISPLAY RACK

Herschel H. Hanshaw, Pharr, Tex.

Application May 21, 1951, Serial No. 227,409

2 Claims. (Cl. 211—86)

1

This invention relates to new and useful improvements in display devices and the primary object of the present invention is to provide a counter mounted display rack for belts that will retain the belts in a vertically disposed position for display purposes.

Another important object of the present invention is to provide a belt display rack including a novel and improved mounting means whereby the same may be quickly and readily applied to or removed from a display counter in a convenient manner.

A further object of the present invention is to provide a belt display rack including a horizontally disposed panel having a plurality of slots therein that are sufficiently wide to accommodate belts with buckles attached to the belt disposed on the upper face of the panel to provide a means for withdrawing the belts from the panel.

A still further aim of the present invention is to provide a belt display rack that is extremely small and compact in structure, neat and attractive in appearance, inexpensive to manufacture, assemble and disassemble, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view of the present display rack.

Figure 2 is a vertical sectional view showing the present invention mounted upon a display counter;

Figure 3 is an enlarged transverse vertical sectional view taken substantially on the section line 3—3 of Figure 1;

Figure 4 is an enlarged fragmentary bottom plan view of Figure 1;

Figure 5 is a view similar to Figure 2 but showing the device modified and in section to be used as a permanent fixture;

Figure 6 is a reduced bottom plan view of the invention in further modified form; and

Figure 7 is an enlarged detail fragmentary longitudinal sectional view taken substantially on the plane of section line 7—7 of Figure 6.

Referring now to the drawings in detail, wherein for the purposes of illustration, there is disclosed a preferred embodiment of the present invention, the numeral 10 represent an elongated and flat support panel having a plurality of spaced parallel longitudinally extending slots 12

5 at each of its end portions. The slots 12 are sufficiently wide to accommodate belts, but buckles or loops attached to the belts will rest upon the upper face of the panel, since the slots are too small to permit buckles to pass therethrough. The slots are formed with transversely convexed longitudinal edges to prevent the scratching or marking of belts extended through the slots.

10 A plurality of substantially triangular walls 14 are secured to the undersurface of the panel 10 by fasteners 15 that extend downwardly through the panel 10 and into the upper edge 16 of each of the walls 14. The upper face of the panel 10 is formed with countersinks for receiving the heads of the fasteners 15. It is preferred that one of the walls 14 be disposed at each end of the panel 10 with an additional wall 14 at the middle of the panel 10 as shown in Figure 1.

15 The undersurface of the panel 10 is provided with recesses 18 that receive the horizontal leg portions 20 of resilient angle members 22. The vertical leg portions 24 of the members 22 are spaced from the rear vertical edges of the walls 14 and coat therewith in yieldingly gripping the upstanding glass wall 28 of a display counter 30 having a molding 32 that seats against the walls of notches 34 in the lower corners or ends 38 of the walls 14.

20 Additional fasteners 36 extend upwardly through apertures provided in the leg portions 20 and enter the inner walls of the recesses 18.

25 The panel 10 may be of any suitable material, such as plastic, wood or metal and this is likewise true for the supporting walls 14 that are removably secured to the undersurface of the panel 10 by the fasteners 15.

30 In practical use of the present invention, the upper edge of the glass wall 28 is inserted upwardly between the edges 26 and the leg portions 24 to be yieldingly held therebetween. The walls 14 are supported upon the molding 32 with the upper edge of the molding positioned in the notches 34. Belts are then extended through the slots 12 with the buckles attached to the belts resting upon the upper face of the panel 10.

35 The panel 10 is supported sufficiently high to permit inspection of the belts extended through the slots 12 and the belts may be readily removed by the gripping of the buckles attached thereto.

40 The device thus described may be used as a permanent fixture, as shown in Figure 5, by aligning the metal bracket 20a with brace 26a 55 and by securing the same together by fasteners

21 that extend through a structure member S disposed therebetween.

Also, the device as shown in Figures 6 and 7 may be composed of elongated longitudinally aligned sections 10' with the abutting ends of adjacent sections being rabbeted as at 13, to form a flush joint. In such construction, the brace 26' and brackets 20' will underlie the joints and be secured to the inter-engaged rabbeted ends to hold adjacent sections together.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and the scope of the appended claims.

Having described the invention, what is claimed as new is:

1. A belt display rack comprising an elongated flat support panel having a plurality of slots therein to accommodate belts, said slots being relatively narrow to prevent buckles from passing therethrough, a plurality of attaching walls 30 depending from the panel and including lower

ends having recesses therein to receive the molding of a display counter, and vertical legs attached to the panel and coacting with the walls for clampingly receiving the upstanding glass wall of a display counter.

2. In a display counter having a molding and an upstanding glass wall resting against the molding, a belt display rack comprising a horizontal panel having a plurality of slots therein for receiving belts, a plurality of walls depending from the panel and including lower ends having recesses therein receiving the molding, said panel having an undersurface with recesses therein, and a plurality of resilient angle members having horizontal leg portions secured in said recesses and vertical portions coacting with the walls to clamp the glass wall therebetween.
